CONTROL PANEL FOR A LAUNDRY APPLIANCE

Dudley P. Combs, Newton, Iowa, assignor to The Maytag Company, Newton, Iowa, a corporation of Delaware

Application March 29, 1956, Serial No. 40,835

Term of patent 14 years

(Cl. D49—1)

Figure 1 is a view in front elevation of a control panel for a laundry appliance embodying my new design;

Figure 2 is a side elevation of the control panel in Figure 1 taken at the left end thereof;

Figure 3 is a sectional view of the control panel of Figure 1 taken along line 3—3 thereof;

Figure 4 is a sectional view of the control panel of Figure 1 taken along line 4—4 thereof; and,

Figure 5 is an enlarged fragmentary view of the pattern illustrated on the lower panel of Figure 1.

The dominant features of my design reside in the portions shown in full lines.

I claim:

The ornamental design for a control panel for a laundry appliance, substantially as shown and described.
